UNITED STATES PATENT OFFICE.

JAKOB RANTASÁ, OF VIENNA, AUSTRIA-HUNGARY.

MOTOR-SLEDGE.

1,162,806.

Specification of Letters Patent.

Patented Dec. 7, 1915.

Application filed June 5, 1912. Serial No. 701,809.

To all whom it may concern:

Be it known that I, JAKOB RANTASÁ, a subject of the Emperor of Austria-Hungary, residing at Vienna, Austria-Hungary, have 5 invented certain new and useful Improvements in Motor-Sledges, of which the following is a specification.

The invention relates to improvements in motor sleighs especially of the type patented 10 by Letters Patent 922332 of May 18, 1909, according to which the yieldingly mounted propeller can be adjusted in vertical direction in accordance with the depth of the snow on which the sleigh is traveling.

15 The invention consists in the arrangement of the blades upon a comparatively wide drum in such a manner that the snow, when the blade drum is in its lowermost position, is compressed by this drum, so that the 20 blades engaging the snow will find resistance enough to effectively advance the sleigh. The blades are disposed in an angle of about 45° to the radius of the drum, thus increasing greatly the efficiency of the blade 25 drum.

The invention further consists in improved 30 means for securely mounting the blade drum and for steering the sleigh. The journal of the axle of the blade drum is rotatably mounted in a bearing frame adjustable in vertical direction and connected with slides guided between vertical standards of the frame and actuated by means of a train of pulleys and chains. For preventing the 35 driving chain of the blade wheel from slackening or from being thrown off when the blade wheel is raised or lowered a chain tensioning device is provided. The steering of the sleigh is effected by steering shoes in 40 frictional contact with the snow or ice and steering the sledge when actuated by the operation of a lever near the driver's seat. Finally the prongs of the blade wheel are laterally bent out of the plane of said wheel 45 so as to offer greater resistance to the ice or frozen snow.

In the accompanying drawing: Figure 1 is a side view of the motor sleigh. Fig. 2 is a side view of a sleigh constructed according 50 to the present invention after the removal of the rear part of the body wall of the sleigh. Fig. 3 shows the rear part of the sleigh in side view on an enlarged scale. Fig. 4 is a section on line A—B of Fig. 3. Fig. 5 shows in perspective view the journal of the blade wheel shaft. Fig. 6 is a

perspective view of the lower part of a steering shoe. Fig. 7 is a perspective view of the steering mechanism. Fig. 8 shows the arrangement of springs used in connection with the steering mechanism. Fig. 9 shows the blade wheel in side elevation. Fig. 10 is a plan view thereof partly in section. Fig. 11 shows a modified form of the blade wheel. Fig. 12 is a perspective view 65 of the prongs.

The sleigh comprises the runners 1, the frame 2, the drive mechanism 3, the propelling mechanism and the steering mechanism. The driving mechanism 3 consists of 70 a motor and the usual transmission elements (couplings, gearings and the like) and transmits its power by the intermediary of a chain drive upon the propelling mechanism which is arranged in the rear part of 75 the sleigh. The propelling mechanism consists of a blade wheel 4, the blades 5 of which are secured to a comparatively wide drum 6, while their free ends connected to a rim 7 are provided with sharp spikes or teeth 8. 80 As shown in Fig. 4 the blade wheel 4 is keyed to a preferably square axle 9 the rounded end pivots 10 of which are mounted on ball bearings within a sleeve 11 provided with an elongated slot into which a suitable 85 key or the like is working for allowing a displacement of the axle in a horizontal direction while simultaneously preventing a rotation of the same. The support 12 of the ball bearing is provided at both of its 90 ends with horizontal pivots 13 which rest in brackets 15 united by means of connecting plates 14 so as to form a supporting frame. This arrangement allows a rotation of the shaft in different planes, by raising or lowering 95 the two ends of the same to different planes.

In order to prevent an accidental displacement of the axle in a horizontal plane, spiral springs 16 are arranged between the 100 square part of the axle and the bearings. The above mentioned sleeve 11 may also be arranged on one side only in which case the springs between the square part and the body of the bearing can be dispensed with. 105

The supporting frame is slidably mounted upon a plate 17 which itself is on both sides rigidly connected with slides 18. The 110 slidable connection between the plates 14 and the plate 17 is preferably effected by common screw bolts 19 which also unite the plates 14 and the brackets 15. These bolts

pass through slots 20 of the plate 17 and are provided within the same with guiding anti-friction rollers 21. Vertical bolts 22 connected to the frame are surrounded by coil springs 23 bearing with one of their ends 5 against the upper face of the plates 14 and with their other ends against the lower face of a cross-bar 24 through which the bolts pass (see Fig. 3). Upon the ends 22' of the bolts 22 extending beyond the cross-bar, 10 springs are placed in a similar manner as the springs 23 which bear against the upper face of the cross-bar and the end flanges 25 of the bar and thus absorb the shock received by the lower springs. 15

The slides 18 are preferably mounted upon guide rails made of angle irons or tubes 26 (Fig. 4) secured to the frame work of the sleigh, the connection between the 20 slides and the guide rails being effected by means of bolts 29 passing through rollers 27 which rotate within a guiding slot 28 between the angle irons 26.

By the above described arrangement three 25 different independent movements can be imparted to the shaft, namely an oblique adjustment in the vertical plane, on account of the rotary adjustment of the bearings, furthermore a temporary parallel movement in the vertical plane on account of its resilient arrangement in the bearing frame, and finally a constant adjustment in the vertical frame on account of its rigid connection with the slides 18.

30 The slides are operated from the driver's seat by means of a chain drum 30 which is actuated by a hand wheel 31 and by two chains 32 and 33 passing over pulleys 34 and 35, 36 and 37, secured to the frame at 38 and 39, respectively, and connected to the slides 18 at the connecting plate 17, said pulleys when operated lowering or raising the slides according to the direction of operation.

45 It is obvious that chain drums with hand wheels which are connected by a common axle and which can be adjusted against each other may be arranged upon both sides of the sleigh.

50 The necessary displacement of the blade wheel is dependent in each case from the condition of the road. When the ground is frozen or covered with frozen snow the blade wheel is lowered only to such an extent that the prongs or spikes firmly engage the ground, whereas in case the road is covered with newly fallen snow, the wheel is lowered to such an extent that its mantle dives below the surface of the snow and the 55 drum compresses the same.

60 As the distance between the chain wheel 40 mounted upon the shaft 9 of the blade wheel and the driving wheel 41 varies constantly on account of the adjustment or 65 displacement of the drum blade wheel or its

shaft, the connecting chain is liable to be loosened or slackened and to be thrown off. In order to prevent this a chain tensioning device is provided which comprises two-forked pivotally connected levers 42, 43, one 70 of which, 42, is pivotally mounted upon the axle 9 of the blade wheel, while the other is similarly mounted upon the axle of the driving wheel 41, the lever 43 is extended over its pivotal point of connection with the 75 lever 42 and carries at its free end a guide chain wheel 44 over which the chain 45 passing over wheels 40 and 41 passes also. The axle of the chain wheel 44 with its bearing sleeve is arranged in an elongated slot 46 of the lever 43 in such a manner that a lengthening or shortening of the distance between the wheels 44 and 41 is possible. This arrangement allows of keeping the chain constantly tensioned as 80 the guide wheel is moved outwardly when the two centers of the shafts are approaching each other whereas, when the two centers of said shafts are withdrawing from each other an inward movement of the guide 85 chain wheel is effected so that the chain always remains tensioned.

The steering of the sleigh is effected by means of two steering shoes 48 which are pivotally connected to a front bracket 47 of the frame 2 and possess strong central ribs 49 provided with grooves 66 at their lower faces. Each of the steering shoes is secured to an arm 61 pivoted at one end to the bracket 62 of the shoe and at the other end to a shaft 50. To the bracket 62 is also secured by bolts, etc., a pair of cylindrical sleeves 63 receiving strong coil springs 54 compressed by pistons and piston rods 51 jointly connected to arms 60 and a rod 64. 95 The other end of this rod 64 is connected to the shaft 50 and the other end of the arm 60 is pivotally secured to the lower end of the shaft 50 connected to the arm 61. On 100 this end the casing 63 is tightly closed by a stuffing box. The shaft 50 extends vertically from the bracket through the frame 2 and is connected at its free end to a steering lever 57 which is suitably coupled with the steering lever of the second steering shoe 105 by bars 58 and which can be actuated by means of a rope or chain 59 passing around guide rollers 65 and secured to the bars 58 with one of their ends and passing over the steering wheel so that by the 110 operation of the steering wheel the steering shoes can be guided at will from the seat of the driver. The coil springs 54 exert a pressure against the upper surface of the steering shoe and also against the 115 arm 64 thus tending to always press the steering shoes against the road bed. If now the levers 57 are operated the friction between the steering shoes and the snow covered surface of the road bed or the ice upon 120 125 130

the same will effect a steering of the sleigh by the oscillation of the shaft 50 thus providing a reliable steering means. At both sides of the steering shoes the same are provided with a covering 55 of strong sheet metal forming toward the front a sharp edge so as to prevent the entrance of snow into the shoes and to offer friction surfaces which allow of the ready steering of the sleigh when traveling in deep snow.

In place of the steering shoes one or two suitable disks provided with ribs or the like may be employed, in this case, or if only one steering shoe is employed, it is advantageous to operate the same from a central axis so that the sleigh is steered from one point of oscillation.

The blades 5 of the blade wheel are placed on the drum 6 respectively secured to the spokes 71 projecting through the outer face of the drum. They are inclined to the spokes on an angle of about 45° as shown in Fig. 9 and may be straight as shown in Fig. 3 or have the form of waves as shown in Fig. 11 so that the snow can easily fall off the blades. At their periphery the blades

are connected by two parallel rims 7 having sharp teeth or prongs provided with lateral projections 73 which are bent alternately to opposite sides.

I claim:

A motor sleigh of the character described comprising in combination, a blade wheel displaceable and adjustable in vertical direction, a shaft for said wheel journaled in displaceable bearings of the sleigh frame, a driving sprocket wheel, a driven sprocket wheel upon the axle of said shaft, a two-armed lever connecting both wheels having arms of unequal length pivotally connected, a sprocket wheel at the extremity of the longer arm and a chain guided over said sprocket wheel adapted to be tightened in harmony with the changing relation of said shaft, and means for operating said wheels, substantially as described.

In testimony whereof I affix my signature in presence of two witnesses.

JAKOB RANTASA.
